UNITED STATES PATENT OFFICE.

THOMAS F. HORNADAY, OF CHICAGO, ILLINOIS, AND GUSTAVUS E. KITTELBERGER, OF SHELBY, OHIO, ASSIGNORS TO THE AUTOCALL COMPANY, OF SHELBY, OHIO, A CORPORATION OF OHIO.

SUPERVISORY ALARM SYSTEM.

Application filed February 19, 1920. Serial No. 359,873.

The present improvements, relating, as indicated, to a supervisory alarm system, is illustrated as applied to a so-called automatic fire extinguishing system, in which a pipe or series of pipes extends throughout the building to be protected, such pipes being provided with sprinkler heads that open whenever subjected to a predetermined temperature, and are constantly kept filled with water, usually from a supply tank at a higher elevation, so that when said heads open a stream or spray of water will be discharged at the point of danger. The present alarm system is intended primarily to guard against unwarranted, accidental or unintentional shutting off of the supply of water to such a system, it being understood that the main supply lines or pipes require to be provided with valves in order to enable the shutting off of portions of the system for repairs and other purposes. In other words, the object of the invention is to give notice of the shutting off of any such valve at some central station or stations, so that those responsible for the safety of the building may be advised and so make investigation as to the occasion for shutting off the supply of water, as well as see that such valve is promptly opened again. A further object is to provide a simple apparatus for the purpose stated, one that will not readily get out of order, and require a minimum of attention. A further object is to provide a plurality of warning signals as well as a permanent record whenever a valve is thus opened, in order that such opening may not escape the vigilance of those concerned.

To the accomplishment of the foregoing and related ends, said invention, then, consists of the means hereinafter fully described and particularly pointed out in the claims, the annexed drawings and the following description setting forth in detail certain mechanism embodying the invention, such disclosed means constituting, however, but one of the various mechanical forms in which the principle of the invention may be used.

In said annexed drawings:—

Fig. 1 is a diagram or plan showing the general wiring scheme of our improved system as applied to a building equipped with automatic fire extinguishers; Fig. 2 is a more detailed wiring diagram of the system showing details of the apparatus both for trans-

mitting and receiving signals; Figs. 3 and 4 are respectively a front and a side elevation of the signal transmitting device or alarm box, which forms a feature of the system, the scale being larger than in Fig. 1; Fig. 5 is a detail view in front elevation of the gear train and escapement removed from its associated mechanism as disclosed in Fig. 3; Fig. 6 is a diagrammatic view showing the main circuits of the system just prior to setting for the alarm, with the rack bar in lowered position; Fig. 7 is a diagrammatic view showing the main circuits of the system, when set to receive an alarm, the rack bar being elevated, and the pallet locked against movement; Fig. 8 is a diagrammatic view showing the code wheel in position to operate the bell and register, and showing the trouble buzzer circuit, and Fig. 9 is a diagrammatic view showing the lamp circuit for indicating, when closed, that the system is not in set condition to record a signal from the code wheel.

As indicated in Fig. 1, a number of supply pipes or risers 1 are ordinarily required in an automatic fire extinguisher system of any extent, each such pipe, for example, supplying one floor of the building, or a portion of such floor if the latter be of considerable area. In each such pipe, for reasons previously stated, it is desirable to have a shut-off valve 2, so that if one of the sprinkler heads thus connected therewith should develop a leak, or a change in the arrangement of the heads be required to be made, the supply of water to the branch pipes that carry such heads can be temporarily shut off.

Accordingly, in connection with each such valve we provide a signal transmitting device 3 with suitable circuit connections as shown in detail in Fig. 2, whereby, upon closing of any particular valve, various signal devices will be actuated in selected offices about the plant or elsewhere, as desired. Thus in the suggestive scheme shown in Fig. 1, bells 4 are installed in the rooms of the chief engineer, fire chief, superintendent and president, respectively, along with recording devices 5, while in addition there is shown in the rooms of the chief engineer and the fire chief respectively, a luminous signal in the form of a red light 6, and in the room of the fire chief a buzzer 7. Each of said signal devices is shown in Fig. 1 as connected

with a conduit 70 carrying the usual trunk and individual cables.

As previously indicated, the arrangement of the foregoing devices or pieces of apparatus is shown in detail in Fig. 2, such arrangement being shown in connection with a single valve 2 and appropriate circuit connections. In such illustrated arrangement the parts grouped between the lines *a*, *a* 10 may be regarded as constituting the signal unit, such unit including a bell 4, recording device or register 5, and two lamps 6, a plurality of such lamps being employed so that if one accidentally burns out another 15 will remain to give the signal, and a buzzer 7. In addition such unit includes a relay 8 for said bell 4 and register 5, and a second relay 9 for said buzzer 7. The register 5 is preferably of the tape punching type, such 20 as illustrated, for example, in U. S. Patent No. 840,051 to J. L. Du Frane, dated January 1, 1907, but any other suitable device capable of making a permanent record may be utilized in its stead.

25 The mechanism of the signal device or alarm box 3, shown in the upper left-hand corner of Fig. 2, and on larger scale in Figs. 3 and 4, consists of a gear train, which includes a pinion 10 adapted to rotate a 30 notched sector wheel 11 or other suitable form of code-wheel, in a counter-clockwise direction through the medium of a gear 10^a and a pawl attached to gear 10^a and a ratchet attached to pinion 10, said pawl and 35 ratchet being designated 10^c in Fig. 5. Thus movement of the pinion 10 in the reverse direction has no effect on said wheel 11. There is also fixedly attached to the front of wheel 11, a second wheel 11^b having 40 a single notch as shown.

The speed of the train, and thus of said sector wheel, is regulated by an escapement wheel 12 and a pallet 13. Said escapement 45 wheel 12 is attached to the shaft carrying the pinion 10^b. Stop means are provided, as will be readily understood, whereby such sector wheel, with attached notched wheel 11^b, makes one complete revolution only under the impulse of the weighted rack 20 50 and regulated by gear train mechanism 10^a, 10^b, 12 and 13. During its rotation in the fashion just described, the teeth of the sector wheel serve to open and close contacts 14 and 15 a predetermined number of times, depending upon the number of such teeth, it being understood that each signal or alarm box will have its sector wheel provided with a different number or arrangement of teeth, whereby the signal sent in therefrom can be 55 identified. At the same time, when such sector wheel starts to turn, contacts 16 and 17 are forced apart so as to open the circuit connected therewith, and hold the same open until the wheel returns to its starting position, when such circuit is again closed.

To actuate the train of gears in the fashion just described, a weighted rack 20 is preferably employed, such rack engaging a pinion that forms one of the said train of gears. This rack is extended downwardly to constitute a plunger type armature 21 of a solenoid relay 22, a weight 23 being attached to the lower projecting end of such armature. Passage of current through the solenoid is effective to raise such armature while the 75 cutting off or breaking of the current therethrough leaves the armature free to drop under the influence of the weight, and so causes actuation of the train of gears by means of the rack. A stop 24 provided with 80 an adjusting slot 24^b, and secured by a screw 24^c to the side of the solenoid mounting, and another stop 24^a within the solenoid core engaged with armature 21 respectively serve to properly limit the downward and upward 85 movement of said armature and thus of the rack.

Means are also provided for retaining such weighted armature and thus the rack, in their raised position, irrespective of the 90 flow of current through the solenoid, such means consisting of a holding relay 25 that when magnetized pulls forward armature 26 and moves the extension arm thereof 26^a and stop finger 26^b up against pallet 13 (see 95 Figs. 3 and 7,) holding the same in place, and so locking the escapement wheel 12 and connected train of gearing against rotation. The current through solenoid 22 is automatically shut off when the rack reaches the 100 upper limit of its movement by the engagement of such rack with a spring contact 27 thereby separating same from a second contact 28, and thereby breaks the circuit through the winding of the solenoid 22. 105 When this occurs, however, the holding relay 25 is intended to be magnetized so as to retain the pallet in place as just described, the object of the foregoing arrangement being to require the solenoid relay to be energized 110 only while pulling up its weighted armature, since an unnecessary amount of current would be consumed if the solenoid relay were required, not only to pull up such weight, but to hold it normally in place. 115 The holding relay on the contrary requires only a very small amount of current, and the current consumption is thus minimized by utilizing it, through the medium of pallet 13, to normally hold the rack, and thus the 120 signal transmitting device, in what may be termed their set position.

The sprinkler system supply pipe 1 is shown at the right of Fig. 2, the valve 2 therein being illustrated as a familiar type of gate valve which is adapted to be opened and closed by the rotation of a hand-wheel, which does not need to be further explained. Normally of course this valve is open so that the distributing pipes or lines leading 125 130

from such pipe may be supplied with water under a proper head. Associated with the valve 2 is a switch 31 that is shown merely in diagrammatic form in the drawings, 5 since the details of its construction have nothing to do with the more general features constituting the present invention. As shown in Fig. 2 this switch comprises contacts 32 and 33 that, in the normal open 10 condition of the valve, are closed, but are arranged to be separated immediately upon closing movement of the valve being initiated by rotation of the aforesaid hand-wheel, the upstanding arm and lateral extension 32', carrying the contact 32 away from the contact 33, fixed to the supporting plate 33'. These contacts in the valve switch are included in the positive side 34 of the main power circuit, the source of 15 power or current being shown as consisting of a battery 35, and when such contacts are closed they allow current to flow through the line 36 to a terminal 37 on the signal transmitting device, or alarm box, that is connected with contact 16. This contact 20 being normally closed against contact 17, the current passes through them and thence to contact 27 which, as described above, is normally held open by the rack. The current 25 accordingly travels through the winding of the holding relay 25 to terminal 38 in said alarm box, the last mentioned terminal being connected with a terminal 39 in the recording station which is in turn connected to the negative side of the main battery, thus 30 completing the circuit.

With the contacts 14 and 15 in the alarm box normally closed, current flows from the positive side of the main battery 35 40 connected with terminal 40 in the recording station, through terminal 41 in said alarm box to said contacts 14 and 15; thence to terminal 42 in the alarm box; thence to terminal 43 in the recording station; thence 45 through the winding of the register and alarm bell relay 8, to terminal 44 in the recording station, which is on the negative side of the line. Under the circumstances 50 stated, said register and alarm bell relay is energized so as to hold its armature down, and thus to separate contacts 45 and 46 controlling the shunt or sub-circuit 47, which 55 parallels a portion of the main circuit and in which the bell 4 and register 5 are preferably included in series as shown, although they may be operated in multiple, if desired. The result of the separation of 60 contacts 14 and 15 will obviously be to break the circuit through the relay, thus closing said contacts and the shunt circuit through such bell and register, as a result of which both the latter are actuated. The means for separating the contacts 14, 15, are the 65 projections on the code wheel 11, as is clearly shown in Fig. 8.

The winding of the buzzer relay 9 is connected through leads 50 directly across the power leads at terminals 40 and 51 in the recording station, as a result of which such relay is normally energized to pull its armature down and separate contacts 52 and 53. When these contacts are closed, current is 70 allowed to flow from dry cells 54, constituting an independent battery for the buzzer, and thus cause it to vibrate and send in an 75 alarm. The buzzer relay is used as a trouble relay only to give warning in case the main line battery is cut off.

The red lights 6, 6 are connected in multiple in a shunt circuit 55 extending from terminal 51 through terminal 57 in the terminal block of the recording station, from said last mentioned terminal to terminal 58 in the alarm box and thence through contacts 59 and 60 controlled by armature 80 26 of holding relay 25 to the other side of the main circuit. The arrangement of contacts 59 and 60 is such that whenever the holding relay becomes demagnetized so as to allow its armature to fall back, said contacts are closed, thus completing the shunt circuit and causing the lights to burn.

The construction of the several constituent devices or pieces of apparatus and the circuit connections of the system have now 95 been described, it is believed, in sufficient detail to warrant a general statement of the mode of operation of the system, which may best be understood by reference to Figs. 6, 100 7, 8 and 9.

Assuming the sprinkler valve 2 is open, the contacts in the valve switch 31 are closed, causing current to flow over line 34 and line 36 as previously explained, passing through the winding of the solenoid relay 22 due to 105 the contacts 27 and 28 being closed, so as to energize such relay and pull up its plunger armature 21 with attached weight 23. The rack extension 20 of such armature is simultaneously raised until, by engaging contact 27, it separates the latter from contact 28 and breaks the circuit to such solenoid relay winding. When the circuit is broken in this fashion, the weighted armature does not fall back, because, when the 110 contacts in the sprinkler valve switch are closed, the holding relay 25 is also magnetized, pulling forward its armature 26 and moving the extension arm 26^a and stop finger 26^b up against pallet 13 so as to lock the escapement wheel 12 against rotation (see Figs. 3 and 7). At the same time that this armature is pulled up, contacts 59 and 60 are broken, causing the red lights 6 to 115 go out.

The circuit is now normally closed and ready for the next alarm signal to come in upon the closing of the valve 2. If it is undertaken to close such valve, the contacts 32 and 33 on the valve switch are immediately 120 125 130

separated, so as to break the circuit through lines 34 and 36, and thereby cause the holding relay 25 to become de-magnetized. As a result the armature of such holding relay is allowed to fall back, which in turn releases pallet 13, the escapement wheel 12 now being free to rotate, subject to the speed regulating effect of the pallet. Accordingly, the weighted armature, with rack, begins to drop, starting the train of gears 10 in motion and causing the sector wheel 11 and attached wheel 11^a to make one complete revolution. When said wheel 11^b starts to turn, contacts 16 and 17 open the circuit and hold it open until the wheel returns to its starting position. The object, in other words, of these contacts is to keep lines 34 and 36 broken, so that in case the switch at valve 2 should be closed immediately after it is opened, before, in other words, the signal could otherwise be completed, a complete signal nevertheless will be sent in and register the valve number, without being interrupted. The construction in question also insures that the sector wheel 11, or code wheel as it may also be called, will stop at the correct position to give a full alarm the next time; otherwise, if the valve 2, for example, were to be thus opened and thereupon closed quickly, such sector wheel would be stopped in the middle of a signal, and the next time the valve was opened so as to operate its switch, the remaining part of the first call would come in, and the number indicated would not be correct.

It will be understood that during the time the sector wheel 11 makes its complete revolution, a code signal is sent in, depending on the number of notches in the sector wheel, this being done by opening and closing contacts 14 and 15, as previously explained. When these contacts are separated, the register and alarm bell relay 8 is de-magnetized, causing its armature to fall back so as to close contacts 45 and 46 and thereby energize the sub-circuit including bell 4 and register 5, causing their armature to operate, which in turn registers the impulses on the register tape and sound the bell, respectively, in consonance with the number and timing of the impulses sent.

Contacts 14 and 15 close immediately after the code teeth on the sector wheel pass by without waiting for the complete rotation of the wheel and contacts 27 and 28 are also brought together, due to the weight falling back and pulling the rack away from said contact 27, in which position they remain until the contacts in the valve switch are closed again.

When the holding relay 25 becomes demagnetized, due to the separation of the valve switch contacts, its armature in falling back connects contacts 59 and 60 in the

shunt or sub-circuit 55 that includes the red lights 6, thus causing them to burn. As previously explained, two such lights are preferably utilized, being connected in multiple so as to insure a visual signal in case one should burn out. These lights remain burning until the holding relay is again energized, due to the closing of the valve switch contacts.

One of the features of applicants' system, it will be observed, is that the alarm box with code-transmitting device is separate and apart from the switch 31 and so does not need to be located in proximity to the valve 2 but may be at a distance. It is thus feasible to place such box, or a number of boxes, connected with a corresponding number of valves, in a room or compartment by themselves, where they will be secure against tampering as well as safe from factory dust and dirt which might affect their certain operation.

It will be understood, of course, that the ground may be used for the return circuit; in other words, the circuits as shown in Fig. 2 need not be metallic throughout; but as shown in Fig. 1, may be grounded adjacent the valves; also that where several valves under supervision are located close together, they may require but a single alarm box in order definitely to indicate the source of trouble. In such case the wiring scheme may be simplified by combining certain leads into a single trunk line, as need not be explained to those familiar with the art.

Finally, it should be pointed out that our improved system is not necessarily limited to the supervision of sprinkler valves, but may be advantageously employed in a variety of connections, where change in the position or condition of operating devices, of which such valves are merely typical, requires to be reported or recorded at a central station. Obviously, the system may be arranged to send in a signal when a sprinkler, or any other valve, as for example a steam valve, is either opened or closed. Similarly, it may be utilized in connection with temperature control apparatus for heating buildings, in heat-treating furnaces, etc. In such last-mentioned case, the control circuit would be affected by a thermostatically operated switch instead of by a switch connected with a manually operated gate-valve. Accordingly, the reference herein to a valve in a fire extinguisher system, unless the contrary is specifically indicated, is to be understood as connoting any such equivalent apparatus or device which may properly come within the scope of a supervisory alarm system.

Other modes of applying the principle of our invention may be employed instead of the one explained, change being made as regards the mechanism herein disclosed, pro-

vided the means stated by any of the following claims or the equivalent of such stated means be employed.

We therefore particularly point out and 5 distinctly claim as our invention:—

1. The combination with a valve of a fire extinguisher system of a transmitter having a set and a released position, means for resetting said transmitter including an electromagnet, a second electromagnet having means co-operating with the transmitter to hold the transmitter in set position, circuit connections controlled by said valve and including said electromagnets whereby said 10 first electromagnet is controlled to reset the transmitter from released position and said second electromagnet is controlled to hold the transmitter in set position when said valve is opened and whereby said second electromagnet is controlled to release said transmitter when the valve is closed, and other circuit connections including signal responsive devices, said last mentioned connections being controlled by the second electromagnet.
2. The combination with a valve of a fire extinguisher system of a transmitter having a set and a released position, means for resetting said transmitter including an electromagnet, means for cutting out said electromagnet after said transmitter has been reset, a second electromagnet having means co-operating with the transmitter to hold the transmitter in set position, circuit connections controlled by said valve and including said electromagnets whereby said first electromagnet is controlled to reset the transmitter from released position and said second electromagnet is controlled to hold the transmitter in set position when said valve is opened and whereby said second electromagnet is controlled to release said transmitter when the valve is closed, and other circuit connections including signal responsive devices, said last mentioned connections being controlled by the second electromagnet.
3. The combination with a valve of a fire extinguisher system of a transmitter having a set and a released position, means for resetting said transmitter including an electromagnet, means for cutting out said electromagnet after said transmitter has been reset, a second electromagnet having means co-operating with the transmitter to hold the transmitter in set position and to cut out said first-named electromagnet, circuit connections controlled by said valve and including said electromagnets whereby said first electromagnet is controlled to reset the transmitter from released position and said second electromagnet is controlled to hold the transmitter in set position when said valve is opened and whereby said second electromagnet is controlled to release said transmitter when the valve is closed, and other circuit connections including signal responsive devices for receiving said code signal, said last mentioned connections being controlled by the second electromagnet.
4. The combination with a valve of a fire extinguisher system of a code transmitter having a set and a released position, means for resetting said transmitter including an electromagnet, a second electromagnet having means co-operating with the transmitter to hold the transmitter in set position, circuit connections controlled by said valve and including said electromagnets whereby said first electromagnet is controlled to reset the transmitter from released position and said second electromagnet is controlled to hold the transmitter in set position when said valve is opened and whereby said second electromagnet is controlled to release said transmitter when the valve is closed, and other circuit connections including signal responsive devices for receiving said code signal, said last mentioned connections being controlled by the second electromagnet.
5. The combination with a valve of a fire extinguisher system of a code transmitter having a set and a released position, means for resetting said transmitter including an electromagnet, means for cutting out said electromagnet after said transmitter has been reset, a second electromagnet having means co-operating with the transmitter to hold the transmitter in set position and to cut out said first-named electromagnet, circuit connections controlled by said valve and including said electromagnets whereby said first electromagnet is controlled to reset the transmitter from released position and said second electromagnet is controlled to hold the transmitter in set position when said valve is opened and whereby said second electromagnet is controlled to release said transmitter when the valve is closed, and other circuit connections including signal responsive devices for receiving said code signal, said last mentioned connections being controlled by the second electromagnet.

Signed by us, this 3rd day of February, 1920.

THOS. F. HORNADAY.
GUSTAVUS E. KITTELBERGER.
